H. L. CUSICK

IRONING DEVICE

Filed March 28. 1923

**H.L.CUSICK,
INVENTOR.**

BY William A. Hartle,

ATTORNEY.

UNITED STATES PATENT OFFICE.

HYLAND L. CUSICK, OF PITTSBURGH, PENNSYLVANIA.

IRONING DEVICE.

Application filed March 28, 1923. Serial No. 628,219.

The present invention relates to drying and ironing devices, and is especially designed to be used in connection with the semi-stiff and soft collars in common use. 5 It has as some of its more desirable features the following.

The device is portable and easily manipulated, and the use of the sad-iron is eliminated. The face of the collar or collars 10 being ironed is kept in a clean condition, and dust is prevented from lodging thereon until the collars are thoroughly dried.

The device can be used to dry and iron both the soft or lined collars, as well as what 15 are called the semi-stiff collars in common use. Means is provided for placing the soft or lined collars under tension while being dried and ironed, so as to insure them against being wrinkled after they are dried. 20 The semi-stiff collars are found not to need this means of wrinkle prevention, but said tension means can be used in connection with the semi-stiff collars if desired.

Means is also provided for evenly drying 25 the collars being ironed, and also for evaporating the water which is freed from the collars while the latter are in a wet condition.

In the accompanying drawings forming 30 part of this specification I have shown a complete example of the best form so far devised for the drying and ironing device, and also a modified form thereof as will be further explained hereinafter as the description of the device proceeds herein.

35 Figure 1 is a perspective view of the ironing and drying device, shown partly in section for purposes of illustration.

Figure 2 is a side elevation of a baffle-plate used in the device.

40 Figure 3 is an end view of Figure 2.

Figure 4 is a partial longitudinal section of a portion of the device taken on line 4-4 of Figure 1.

Figure 5 is a partial end view of the device shown in Figure 1.

Figure 6 is a perspective view of a tension means used.

Figure 7 is a perspective view of a modified form of the ironing device.

50 In the drawings 1 is a semi-circular sheet of metal, preferably of zinc which has been well oxidized by the weather; 2, 3, 4, and 5 are upright legs usually of band-iron or steel. Each pair of legs is connected by a cross piece 6, and there are feet preferably

provided on the bottom of said legs as shown in the drawings. The metal sheet 1 is attached or mounted on the legs as a means of support, and on the lower edges of said sheet 1 are the returned portions 7, 8 for a purpose 60 described below. The ends of the gutter-like returned portions are closed by metal at points 9, 10 as shown to prevent the egress of any water which may collect in said gutters. A baffle-plate 11 preferably curved is 65 mounted within the semi-circular sheet 1 and is secured on the cross-pieces 6, 6 at points 12, 12 as shown. It is noted that a space indicated by 13, 13 is maintained between the baffle-plate 11 and the sheet 1 so 70 that the heat ascending from the stove 14 after being reduced somewhat in temperature by the baffle-plate, reverberates and gradually passes around the space 13 between the baffle-plate and the ironing and 75 drying metal sheet 1. The purpose of said arrangement being to so reduce the temperature of the heated air that there is no chance of scorching the collars 15, which are reposing on the outer side of the sheet 1. 80

The ends 16, 16 of the device are closed by the bent metal plates 17, 17, the latter having preferably an inwardly turned flange 18, 18 by means of which they are attached to the cross-bars 6, 6 at points 12, 12. One or more apertures 19, can be made in the end-plates 17, 17 for the purpose of further reducing the temperature of the captured gases in the space 13 before mentioned. 20, indicates a hook which may be 90 attached to the semi-circular plate 1 at intervals along its side as at 21, 21, etc. for the purpose of attaching the ends of collars thereto as indicated in Figure 5 of the drawings. The adjusting bar 22 shown in Figure 6 has a number of thumb-screws 23, mounted therein for the purpose of engaging the ends of collars thereon as shown in Figure 1. The adjusting bar 22 has returned ends 24, 24 for engaging the projecting ends 95 25, 25 of the metal plate 1, and when the screws 26, 26 are tightened up against the outer surface of the ends 25 it is evident that the bar 22 is rigidly secured to the device.

It is further seen that by raising the end 27 of the said bar 22 that different lengths or sizes of collars can be attached to the hooks 20 and to the said bar 22. It is noted that the semi-stiff or un-lined collars in common use do not need the tension process provided. 100 105 110 115

ed by the use of the hooks 20 and adjusting bar 22, as they do not tend to wrinkle during the drying and ironing, but that the soft, and lined collar being of double thickness usually needs the tension method of handling.

The use of the ironing device from what has been said it is believed is now evident, the collars 15, are first washed and thoroughly cleansed in the usual fashion, and when thoroughly wet are placed on the outer surface of the zinc semi-circular plate 1 with their face down. The soft collars being placed under proper tension by means of the hooks 20 and adjusting bar 22. The device is then placed on the top of a stove 14, and the ascending heat from the stove meets the baffle-plate 11 and reverberating passes around through space 13, and dries the collars placed on the outer side of the plate 1, and as there is a good deal of adhesion and suction by the oxidized zinc plate 1, the semi-stiff collars readily are held under tension until they are thoroughly ironed and dried, leaving them in a surface condition as if they had been ironed with a sad-iron. In the case of the soft or lined collars the method of attaching their ends to the hooks 20 and adjusting bar 22 accomplishes the same purpose of surface tension while being dried and ironed.

It is further seen that as the face surface of the collars 15, is always underneath that no dust can settle on the usable surface of the collars during the drying process. As the collars have to be thoroughly wet when placed on the ironer, there is considerable water squeezed out of them in handling, and to prevent the water from getting on the stove 14, the gutter-like returned edges 7 and 8 are formed on the plate 1 as before described. It is found in practice also that the water which collects in the gutters usually is entirely evaporated before the collars are dry. The baffle-plate 11 reducing the temperature of the heated air enables the collars to be dried more evenly than would be the case without such means being used.

The portability of the device is self-evident and constitutes one of its most important features, as it can be readily removed from the stove and takes up very little space when not in use.

Attention is directed to the use of zinc which is oxidized on its surface by "weathering" as being the only suitable metal so far found which will exactly accomplish the purpose of the invention, and enable the semi-stiff collars to be ironed well and without the use of the tension means above described.

So important a matter is this use of the oxidized zinc, that new and "shining" surfaced zinc or tin will not accomplish the

purpose, as the collars slip and wrinkle while drying, there being no surface adhesion or longitudinal tension on them. Evidently portions of the collars adhere to the zinc surface, when oxidized zinc is used, and as the little globules of water are evaporated from the collar, little vacuum spaces are formed on the collar surface, thus sucking the said surface snugly to the face of the zinc, and this combined adhesion and suction is more than sufficient to securely place the collar under longitudinal tension during the drying process. It is of course quite evident that if steel or iron were used for the semi-circular plate 1 they would rust after a short time in service and soil the collars while being ironed; also that galvanized iron peels off on the surface; and that copper will form verdigris, so that it is seen that oxidized or weathered zinc with small 85 90 95 100 105 110 115 120 125 130 135 140 145 150 155 160 165 170 semi-circular plate, a series of hooks mounted along one side of said plate, and an adjusting bar mounted along the opposite side of the semi-circular plate for the purpose of creating a longitudinal tension in articles being ironed on the latter.

4. In an ironing device, a bent metal plate having a roughened and pitted surface for creating a strong adhesional and suctional hold on articles placed on said metal plate while in a saturated condition, means for directing the flow of water squeezed from such articles while being dried, and means for storing said flow until same can be evaporated.

5. In an ironing device, a bent metal plate having a pitted surface adapted to create a suctional hold on saturated articles placed thereon, and a series of hooks mounted along one side of the bent metal plate, and an adjusting bar mounted along the opposite side of said plate, for causing a tension

in the saturated articles, and prevent shrinkage in same when fully dried.

6. In an ironing device, a metal plate having a pair of projecting ends formed thereon, an adjusting bar having returned ends formed thereon, an adjusting bar having returned ends thereon adapted to engage the projecting ends of the metal plate, and means for holding the said returned ends of the adjusting bar in pressing engagement with the ends of the metal plate.

7. In a portable ironer, a curved metal plate having a pair of projecting ends formed thereon, an adjusting bar having returned ends thereon for engaging the projecting ends of the said metal plate, and thumb-screws mounted in the adjusting bar for securing the said returned ends thereof against the metal plate.

In testimony whereof, I affix my signature.

HYLAND L. CUSICK.
